ACCORDION GRILL

Mario Pancotti, Bronxville, N. Y.

Application April 9, 1953, Serial No. 24,424

Term of patent 3½ years

(Cl. D56—1)

To all whom it may concern:

Be it known that I, Mario Pancotti, a citizen of the United States and resident of 1468 Midland Avenue, Bronxville, New York, have invented a new, original, ornamental Design for an Accordion Grill, of which the following is a specification, reference being had to the accompanying drawing, forming part thereof, wherein:

Fig. 1 is a perspective view of an accordion grill, showing my new design, and Fig. 2 is a top plan view thereof.

The dotted line partial showing of an accordion in Fig. 1 is for illustrative purposes only.

I claim:

The ornamental design for an accordion grill, substantially as shown and described.

MARIO PANCOTTI.
